DOOR VALANCE BOARD

Hans H. Pautke, Elko, Nev.

Application February 7, 1952, Serial No. 270,331

7 Claims. (Cl. 160—19)

1

This invention relates generally to a valance board and more specifically to a valance board for use over a doorway.

The primary object of this invention is to provide a valance board for use over a doorway which may have the same general configuration as other valance boards over windows in a room having the doorway.

Another object of this invention is to provide a valance board for use over a doorway which conceals the upper portion of the door and doorway, and is adapted to have drapery carried thereby.

Another object of this invention is to provide a valance board for use with a doorway, the valance board having a vertically extending front valance board having a portion which extends into the path of the door when it is being opened, said portion being coplanar with the front valance board but pivotally secured thereto for swinging movement out of the path of the door.

Another object of this invention is to provide a valance board for use with a doorway having means for swinging a portion thereof out of the path of the door which closes the doorway.

A further object of this invention is to provide a valance board for use with a doorway, the valance board having a portion disposed in the path of the door for closing the doorway, said portion being swung out of the path of the door by means operated by the opening of the door.

These, together with various ancillary features and objects of the invention, which will later become apparent as the following description proceeds, are attained by the present invention, a preferred embodiment of which has been illustrated by way of example only in the accompanying drawings, wherein:

Figure 1 is a partial elevational view of a wall of a room having a doorway therein, the valance board, which is the subject of this invention, being mounted above the doorway;

Figure 2 is an enlarged partial transverse vertical sectional view through the doorway of Figure 1 substantially on the section line 2—2 and shows the arrangement of the valance board and its operating means when the door is closed;

Figure 3 is a partial transverse vertical sectional view similar to Figure 2, and showing the position of the means for swinging the portion of the front valance board when the door is slightly open;

Figure 4 is a partial transverse vertical sectional view similar to Figure 2 showing the arrangement of the valance board and its operating mechanism when the door is open; and

2

Figure 5 is an enlarged partial elevational view looking from behind the front valance board towards the doorway and showing the means for pivotally mounting a lever which is part of the operating mechanism of the valance board.

Referring now more specifically to the accompanying drawings, wherein like numerals designate similar parts throughout the various views, it will be seen that the novel valance board, which is the subject of this invention, is shown in Figure 1 as being applied over a conventional doorway 10 in a wall 12 of a room. The edges of the doorway 10 are provided with the conventional boarder trim 14, and the doorway 10 is closed by a conventional swinging door 16. Mounted over the doorway 10 and secured to the wall 12 is the valance board 18, which is the subject of this invention.

Referring now to Figure 2, in particular, it will be seen that the valance board 18 consists of a rear mounting board 20 which is secured to the wall 12 and supports the valance board 18 therefrom. The valance board 18 also includes a top board 22, end boards 24, and a front valance board 26. As is illustrated in the drawings, the front valance board 26 is disposed within the path of the door 16 and prevents the door 16 from being fully opened. In order that the front valance board 26 does not interfere with the opening of the door 16, the front valance board is provided with a swinging portion 28 which is pivotally secured to and in normal coplanar relation with the front valance board 26 by pivot pins 30.

In order to prevent the door 16 from striking the swinging portion 28 of the front valance board 26, there is provided an operating mechanism for swinging the portion 28. The operating mechanism includes a lever 32 which is pivotally secured between the arms of a mounting bracket 34 by a pivot pin 36. The mounting bracket 34 is secured to the rear board 20 adjacent the lower edge thereof. An eye 38 is secured to the underside of the top board 22 in vertical alignment with the pivot pin 36. The lever 32 is provided with a plurality of apertures 40 intermediate its ends. The apertures 40 are adapted to receive one end of a tension spring 42 carried by the eye 38, and the plurality of apertures is for purposes of adjusting the tension of the spring 42.

Referring now to Figures 2, 3 and 4, in particular, it will be seen that once the lever 32 has been rotated clockwise from its normal vertical position that further clockwise rotation will be

urged by the spring 42. In order to prevent rapid clockwise rotation of the lever 32 in response to the spring 42, and also in order to return the lever 32 to its normal vertical position, the lever 32 is provided with a horizontal arm 44. Referring to Figure 2, in particular, it will be seen that when the lever 32 is in its normal vertical position that the arm 44 overlies the top of the door 16 and is in engagement with the underside of the top board 46 of the casing of the doorway 10.

It will be seen by referring to Figures 1 and 5 that the lever 32 and its associated elements are disposed adjacent the unhinged edge of the door 16. By so positioning the lever 16, it is obvious that rotation of the door 16 through a small angle will bring the door 16 into engagement with the lever 32 and its associated arm 44, as shown in Figure 3.

When the door 16 is opened, its front surface strikes the rear of the lever 32 and rotates the lever 32 clockwise to a point where the spring 42 is in a position to urge further clockwise rotation of the lever 32. The spring-urged counterclockwise rotation of the lever 32 results in the engagement of the arm 44 with the upper rear edge of the door 16 to retain the lever 32 against further spring-urged rotation. As the door 16 is further opened, the lever 32 is allowed to further rotate clockwise until it engages the rear side of the swinging portion 28 of the front valance board 26. As the door 16 continues to open, the lever 32 rotates to a horizontal position and at the same time rotates the swinging portion 28 to a horizontal position as shown in Figure 4. When the lever 32 is in a horizontal position, the arm 44 no longer engages the rear of the door 16. The swinging portion 28 of the front valance board 26 having been swung out of the path of the door 16, the door 16 is free to be fully opened.

When the door 16 is closed, its upper rear edge again engages the arm 44 and moves the arm 44 and its associated lever 32 to a position shown in Figure 2. Since the pivot pins 30 for mounting the swinging portion 28 are above the center of gravity of the swinging portion 28, the swinging portion returns to its original position by the force of gravity.

In order that draperies may be supported by the valance board 18, there is secured to the underside of the top board 22 a drapery supporting rod 48.

Although the valance board 18 is illustrated as having a front valance board 26 and a swinging portion 28 of a fanciful design, it is obvious that the design of the valance board for over the doorway 10 will have the same design as the valance boards for use over the windows (not shown) of the room.

From the foregoing, the construction and operation of the valance board will be readily understood, and further explanation is believed to be unnecessary. However, since numerous modifications and changes will readily occur to those skilled in the art after a consideration of the foregoing specification and accompanying drawings, it is not desired to limit the invention to the exact construction shown and described, nor is it desired to limit the invention to a doorway having a single door as it is designed for use with French doors also, and also suitable modifications and equivalents may be resorted to, falling within the scope of the appended claims.

Having described the invention, what is claimed as new is:

1. A door valance for a doorway having a vertical front valance board which is adapted to be mounted over said doorway in the path of a swinging door which is mounted for closing said doorway, a portion of said front valance board being swingable out of the path of said door upon the opening of same, said swinging portion being pivotable about a horizontal axis, said axis being above the center of gravity of the swinging portion whereby said swinging portion is urged to its normal position coplanar with the remainder of said front valance board.

2. A door valance for a doorway having a vertical front valance board which is adapted to be mounted over said doorway in the path of a swinging door which is mounted for closing said doorway, a portion of said front valance board being swingable out of the path of said door upon the opening of same, said swinging portion being pivotable about a horizontal axis, said axis being above the center of gravity of the swinging portion whereby said swinging portion is urged to its normal position coplanar with the remainder of said front valance board, means responsive to the opening of the door for swing-
ing said portion out of the path of the door.

3. A door valance for a doorway having a vertical front valance board which is adapted to be mounted over said doorway in the path of a swinging door which is mounted for closing said doorway, a portion of said front valance board being swingable out of the path of said door upon the opening of same, means engageable with the door and responsive to the opening thereof, said means being engageable with said portion to swing the same out of the path of the door, said means for swinging said portion including a spring-urged lever which is engageable with said portion for swinging same, means for retaining said lever in an inoperative position.

4. A door valance for a doorway having a vertical front valance board which is adapted to be mounted over said doorway in the path of a swinging door which is mounted for closing said doorway, a portion of said front valance board being swingable out of the path of said door upon the opening of same, means engageable with the door and responsive to the opening thereof, said means being engageable with said portion to swing the same out of the path of the door, said means for swinging said portion including a spring-urged lever which is engageable with said portion for swinging same, means for retaining said lever in an inoperative position, said retaining means including a depending arm on said lever, said arm being engageable by the upper edge of the door to be moved thereby in and out of its lever retaining position.

5. A door valance for a doorway including a vertical front valance board which is adapted to be mounted over a doorway in a path of a swinging door which is mounted for closing the doorway, a portion of said front valance board being swingable out of the path of the door upon opening of the same, an actuating lever pivotally mounted rearwardly of said front valance board portion, said lever engaging said front valance board portion and pivoting the same to a horizontal position upon opening of the door.

6. A door valance for a doorway including a vertical front valance board which is adapted to be mounted over a doorway in a path of a swing-

ing door which is mounted for closing the doorway, a portion of said front valance board being swingable out of the path of the door upon opening of the same, an actuating lever pivotally mounted rearwardly of said front valance board portion, said lever engaging said front valance board portion and pivoting the same to a horizontal position upon opening of the door, said lever being spring urged towards said front valance board portion, means on said lever engageable with the door for restraining pivoting of said lever in response to urging of said spring when the door is closed.

7. A door valance for a doorway including a vertical front valance board which is adapted to be mounted over a doorway in a path of a swinging door which is mounted for closing the doorway, a portion of said front valance board being swingable out of the path of the door upon opening of the same, an actuating lever pivotally mounted rearwardly of said front valance board portion, said lever engaging said front valance board portion and pivoting the same to a hori-

10

5

zontal position upon opening of the door, said lever being spring urged towards said front valance board portion, means on said lever engageable with the door for restraining pivoting of said lever in response to urging of said spring when the door is closed, said front valance board portion having its mounting means above its center of gravity whereby the front valance board portion is urged to a vertical position.
